MICHAEL SWEENEY'S
DESIGN FOR LAMP CHIMNEYS.

D4983

PATENTED JUN 6 1871

WITNESSES.

S. M. Howard
John A. Gray

INVENTOR.

Michael Sweeney,
for J. B. McLain
Attorney.

United States Patent Office.

MICHAEL SWEENEY, OF MARTINSVILLE, OHIO.

Design No. 4,983, dated June 6, 1871.

DESIGN FOR LAMP-CHIMNEY.

The Schedule referred to in these Letters Patent and making part of the same.

To all whom it may concern:

Be it known that I, MICHAEL SWEENEY, of the town of Martinsville, in the county of Belmont and State of Ohio, have invented and produced a new and original Design for a Lamp-Chimney, of which the following is a specification.

The nature of my design is fully represented in the accompanying drawing, to which reference is made.

I claim as my invention—

The design for a lamp-chimney, as shown.

MICHAEL SWEENEY.

Witnesses:

JNO. MCLURE,
J. B. MCLURE.
